STORAGE WALLET FOR WATCHBAND CALENDARS

Patrick Petrie, P.O. Box 66425,
Los Angeles, Calif. 90066

Filed Jan. 12, 1970, Ser. No. 20,872

Term of patent 14 years

Int. Cl. D3—02

U.S. Cl. D87—3

FIG. 1

FIG. 2

FIG. 3

FIG. 1 is a top plan view of a storage wallet for watchband calendars showing my new design;

FIG. 2 is a bottom plan view thereof; and,

FIG. 3 is an edge view thereof.

I claim:

The ornamental design for a storage wallet for watchband calendars, substantially as shown.
